COMBINATION APRON

Margaret Repitsky, Cleveland Heights, Ohio

Application February 27, 1933, Serial No. 658,737

3 Claims. (Cl. 2—48)

This invention relates to the art of wearing apparel. More specifically, the present invention consists in a combination apron.

The object of the present invention is to provide an improved form of combination apron comprising a main body member of fabric and a panel member of rubber or like material of a water-proof nature, together with improved means for attaching the two members together in different position of relative adjustment.

A further object consists in devising an improved form of means for conveniently and efficiently attaching the body member and panel member of the apron together.

15 A still further object consists in devising such a combination apron which can be conveniently and effectively converted into a single compartment bag or a double compartment bag and in which there may be utilized the same means of attachment as provided for use when employed as an apron.

Other objects will appear from the following specification and claims when considered together with the accompanying drawings.

20 Fig. 1 illustrates in a general way the manner of using the combination apron;

Fig. 2 is a front elevation of the body portion of the apron;

Fig. 3 is an elevation of the panel member;

30 Fig. 4 is a front elevation of the combination apron;

Fig. 5 is a front elevation of the same with the panel member in raised position of adjustment;

35 Fig. 6 is a front elevation of the same with the panel member in lowered position of adjustment;

Fig. 7 illustrates the form of belt employed;

Fig. 8 is a view taken on line 8—8 of Fig. 4;

40 Fig. 9 shows in elevation the device when converted into a single compartment bag;

Fig. 10 is an end elevation of the same;

Fig. 11 is a view taken on line 11—11 of Fig. 9;

45 Fig. 12 shows in elevation the device when converted into a double compartment bag;

Fig. 13 is an end elevation of the same;

Fig. 14 is a view taken on line 14—14 of Fig.

12;

50 Fig. 15 is a partial detail view illustrating the tape ties and their manner of attachment to the body member of the apron; and

Fig. 16 is a vertical sectional view of the same.

The body member 1 consists of fabric, as for instance, cotton or the like, and is of tapered

form with the larger end at the bottom so that the body member may be regarded as having flap portions 1^a at the two sides thereof, as will later more clearly appear.

The panel member 2 is of regular rectangular form of the same height as the body member and consists of rubber or rubberized material of a waterproof nature.

Both the body member and the panel member are provided with apertures or button-holes which are adapted to register with each other when the panel member overlies the body member in the manner indicated in Fig. 4. The apertures in these two members are indicated by reference numerals 3 and 4, respectively.

It will be observed that the apertures 4 are located along the margins of the panel member and that the apertures 3 are located along the line corresponding substantially to the line of division between the main part of the body member 1 and the flap portions 1^a. It is noted also that the apertures 3 and 4 in each case are spaced at equal intervals for purposes to be later explained.

The means for attaching the panel member 2 to the body member 1 consists of tape ties or tie members 5 which are sewed upon the rear side of the body member, that is, upon the side next to the body of the user when worn. These tie members are fastened at their middle points and in proximity to the apertures 3 so that

the ends of these tie members are free, as indicated in the drawings, and they can be extended through the apertures 3 and also through the registering apertures 4 and tied in bow-knots upon the front of the panel member 2.

In this manner, the panel member is effectively attached to the body member and there is produced an attractive appearance.

As an auxiliary means of attaching the panel member 2 to the body member 1, I have provided the button 6 upon one part of each of the tie members, these buttons being located a sufficient distance from the point of attachment of the tie members to the body member so that

the buttons may be extended through the apertures 3 and employed for buttoning the panel member on to the body member in lieu of the bow-knots, as above referred to. That is, the buttons may be employed as a quicker means of attachment.

The belt 7 for the apron consists of a tape or other suitable form of material, the ends of which are adapted to be tied in the form of a bow with the ends of the tie members 5 at the

top of the apron, as indicated in Figs. 4, 5, and 6. It is to be understood that the belt extends about the waist of the user. If so, desired, button-holes may be provided in the ends of 5 the belt member 7 for quicker attachment to the buttons on the uppermost tape members 5.

When it is desired to have the panel member 2 serve as a bib or means of protection for the upper part of the garment of the user, this 10 may be accomplished by positioning the panel member 2 upon the body member 1 in the manner indicated in Fig. 5. That is, the two lower tiers of apertures 4 of the panel member 2 will register with the two upper tiers of apertures 3 15 of the body member 1 and the same means of attaching these two members together, as heretofore explained, will be employed. The upper part of the panel member may then be fastened to the wearing apparel of the user by extending 20 a portion of the garment through the uppermost apertures 4 of the panel member and then applying a pin to the garment upon the outer side of the panel member 2; or any other suitable form of fastening means may be employed. 25 Then, when it is desired to utilize the lower part of the panel member 2 for purposes of kneeling, this may be accomplished by arranging the panel member upon the body member of the apron in the manner indicated in Fig. 6, 30 that is, the two upper tiers of apertures 4 of the panel member will register with the two lower tiers of apertures 3 of the body member and these two members will then be attached together in the same manner as already explained and the belt will likewise be applied in the same manner.

It is to be understood also that if so desired, the panel member 2 may be omitted entirely and the body member 1 may be employed alone 40 as an apron. In this case, the tie members may be retained entirely upon the rear side, that is, the side next to the user, so as to be out of sight. Likewise, when the panel member is employed in the adjusted positions illustrated 45 in Figs. 5 and 6, the tie members which are not in use may be retained upon the rear side of the body member 1 so as to remain out of sight. Or, if desired, the idle tie members may be pulled through their apertures and tied in bow-knots so as to correspond with the other bows, 50 merely for purposes of appearance.

When it is desired to employ my combination apron as a single compartment bag, the panel member is caused to overlie the body member 55 in the usual manner, as indicated in Fig. 4, and then before fastening the body member and panel together, they are folded together in half so as to bring the panel member upon the inside or upon the outside of the bag, as may be desired. In either case, the flap portions 1^a are 60 first turned in so as to be upon the inside of the bag when completed. Then, when the members have been folded together, they may be secured in such position by extending the tie members through the apertures of the panel 65 members and then tying the same together. It should be explained that upon folding the flap portions 1^a inwardly, this fold is made substantially along the line of the apertures 3 so 70 that the flap portions 1^a will not interfere with the tying of the tape members 5 together. These tape tie members which are then located upon the front and rear sides of the bag may be 75 extended about the folded edges of the fabric and thence through the apertures of the rub-

ber panel and then tied together. The belt 7 of the apron may be employed as the handle for the bag by tying the two ends of the belt together with the tie members nearest the top of the bag.

In the form of single compartment bag illustrated in Figs. 9 and 10, the rubber panel is shown upon the inside of the bag. As before explained, the reverse arrangement of bag may also be formed from the combination apron, that is, with the rubber panel upon the outside. In this case, also, the flap portions 1^a will first be folded inwardly and when the apron has been folded in half into the form of a bag, it will be secured in such condition by means of the tie members 5 in substantially the same manner as explained for the other form of bag. In this case, the tie members 5 will first be extended through the apertures 3 of the body member, prior to folding in the flaps 1^a and then through the apertures 4 of the panel member and finally tied together.

When it is desired to convert the combination apron into a two-compartment bag, the body member 1 and the panel member 2 are 100 folded separately in half after first having turned the flap portions 1^a inwardly so as to be upon the inside of the bag when completed. Then the two folded members 1 and 2 are placed together and are secured together in such position by means of the tie members 5. As above explained, here also the flap portions 1^a are folded upon the line corresponding to that of the apertures 3 so that the tie members 5 may readily be extended about the folded edges of 110 the body member 1 and thence extended through the apertures 4 of the panel member. In this case also, the belt member 7 may be employed as a handle for the bag by tying the ends of the belt together with the uppermost tie members. 115

It is to be understood that the manner of extending the tie members through the registering apertures and tying the ends of the same together may be varied according to the desire of the user, and it is to be understood that the present invention is not limited to any one specific manner of use of the tie members in attaching the members together.

Needless to explain, the advantage of being able to form the single compartment bag with 125 the water-proof panel member upon either the inside or the outside consists in the fact that in one case the bag may be employed to contain a wet bathing suit or the like, while in the other case, it may be employed to prevent the entrance 130 of moisture from the outside to the inside of the bag.

Likewise in the two compartment bag, one compartment may be employed to contain wet articles without interfering with the other compartment in which there may be placed other articles without being exposed to the wet condition of the articles in the water-proof compartment.

It should be explained also that the advantage of my particular arrangement of tie members and adjacent apertures, resides in the fact that the tie members may be sewed on to the body member of the apron and extended through 145 the registering apertures so as to serve as a means of attaching the panel member to the body member in a manner equally as efficient as if the tie members were secured upon the rubber panel itself but without the difficulty of 150

attaching the tape tie or other connecting member directly to the rubber panel.

It should be explained also that with the tape form of attaching means, the free end portions thereof may be drawn back through the apertures after they have been tied together, if so desired, so as to conceal the same from view. This same practice may be followed in connection with the present device when employed as a combination apron or when employed either as a single or double compartment bag.

Thus, I have devised a combination apron which is capable of various adjustments when used as an apron and which is also capable of being converted into different forms of bags while at the same time, there may be employed the same means of attachment throughout the various uses to which it may be put.

This device may be constructed at a comparatively small cost and is extremely simple in its several manipulations while at the same time it is extremely efficient in the several uses for which intended.

What I claim is:

1. A combination apron comprising a main body member, a panel member adapted to overlie the body member, said members being provided with registering apertures equi-spaced along the opposite marginal portions thereof, and ties attached to one face of said body member in close proximity to said apertures and adapted to be extended through the registering apertures of said body and panel members and tied when the body and panel members are in folded condition so as to thereby convert the combination apron into a bag.

2. A combination apron comprising a main body member, a panel member adapted to overlie the body member, said members being of equal length and being provided with registering apertures equi-spaced along the opposite marginal portions thereof, and ties attached to one face of said body member in close proximity to said apertures and adapted to be extended through the registering apertures of said body and panel members and tied when the body and panel members are in individually folded condition so as to thereby convert the combination apron into a two-part bag.

3. A combination apron comprising a main body member of fabric, a rubber panel member adapted to overlie said body member, said members being of equal length and said body member having side flaps beyond the edges of the panel member, said members being provided with registering apertures equi-spaced along the opposite marginal portions thereof, the apertures in said body member being located substantially at the inner margins of said flaps, and ties attached to the inner surface of said body member in close proximity to said apertures and adapted to be extended through the registering apertures of said body and panel members and tied when the body and panel members are folded together or separately, whereby the combination apron can be readily converted into either a single compartment bag with the rubber panel upon the inside or outside thereof or into a two compartment bag with the body member and panel member forming the separate compartments thereof.
